UNITED STATES PATENT OFFICE.

ROWLAND N. CHUBB, OF STOCKTON, CALIFORNIA.

RADIANT ANNUNCIATOR-SIGN.

1,371,470.

Specification of Letters Patent. Patented Mar. 15, 1921.

Application filed May 8, 1920. Serial No. 379,769.

To all whom it may concern:

Be it known that I, ROWLAND N. CHUBB, a subject of Great Britain, residing at Stockton, in the county of San Joaquin, State of California, have invented certain new and useful Improvements in Radiant Annunciator-Signs; and I do declare the following to be a full, clear, and exact description of the same, reference being had to the accompanying drawings, and to the characters of reference marked thereon, which form a part of this application.

This invention relates to improvements in annunciator signs such as are extensively used for advertising, display, or other purposes.

The principal object of the invention is to provide a sign structure so constructed and arranged that any combination of letters or numerals may be had, so that the sign may show any desired wording or lettering, without the necessity of making any changes to the sign itself, or replacing certain parts with others.

Another object is to provide a sign in which the various character combinations may be had, which will be visible either by night or by day, without the necessity of employing intricate and expensive mechanism for making such changes in combination, and yet which enables the necessary changes to be readily and easily made in a very short time.

A further object is to produce a sign of the type specified, in which the words or combinations of characters formed will appear very distinctly, and will not have the blurred appearance so common in many such signs.

My improved sign is particularly adapted to be used by theaters, for the display of the names of plays, etc., on the street, which names are changed once a week or thereabout; and for stores and shops, for advertising or calling attention to various articles, in which case the sign may be made large enough to be suspended above the store front, or so small that it may readily be placed in a show window.

The sign may also be used for bulletins, announcements, etc., and installed in offices,

hotels, and other public buildings, and in fact anywhere a sign of this character may be useful.

The construction and operation of my device, and also the installation and maintenance thereof, is a matter of relatively small expense, both as to time and labor, since the keynote of the device is its simplicity, both as to construction and opera- 55 60

These objects I accomplish by means of such structure and relative arrangement of parts as will fully appear by a perusal of the following specification and claims. 65

In the drawings similar characters of reference indicate corresponding parts in the several views.

Figure 1 is a front view of a sign embodying by improved features of construction. 70

Fig. 2 is an enlarged fragmentary section thereof.

Fig. 3 is an enlarged detached view of a form of shutter.

Referring now more particularly to the 75 characters of reference on the drawings, the numeral 1 denotes a face-plate provided with closely spaced sets of openings 2 through-out the area thereof, and preferably, but not necessarily, positioned in regular alinement, 80 so that any letters may be formed which will present a continuous and symmetrical appearance.

In the accompanying drawing I have shown five horizontal rows of openings and 85 in any event an odd number of such rows such as 7, or 9, would preferably be em-ployed, since a good many of the letters of the alphabet have a substantially central horizontal cross-bar, such as "E," "H," 90 "P," "S" and others.

By thus having a row of openings cen-tral of the remainder, the symmetry of out-line of the letters formed is preserved.

Each set of openings is preferably in the 95 form of a Maltese cross, since I believe this design to be the best suited to evenly divide up a given area into an equal number of solid and cut-out portions. The outer edge however could be circular without impairing 100 the feature above set forth.

I have also found that this design attracts

attention thereto, and that it well combines with other sets, when arranged to outline a letter or other character.

The face plate 1 is preferably of sheet metal, or other opaque material.

Such plate, surrounding each set of openings, is pressed outwardly therefrom as at 3, for a distance substantially equal to the thickness of a similar sheet of material.

10 On the inner side of the face plate, and resting closely against that portion not pressed outwardly, is a plate 4 of non-transparent but translucent material, such as white opal glass, or opalescent glass of any 15 color distinctive to the color of the plate 1 may be used.

Positioned in the pressed out portions 3 and bearing closely thereagainst are opaque shields 5 of the same design as the sets of 20 openings 2. These shields have pins 6 projecting through the plate 1 central of the opening-sets. Each pin outside the plate has a cross-bar 7 or similar member so that it may readily be turned by hand or by some 25 suitable implement manipulated by a person below the sign, should the latter be mounted out of normal reach of the operator.

Each solid arm 5^a of the shields is almost the exact width, or a trifle more if anything, of each individual opening 2^a in the opening-sets 2, and each arm and opening is of course exactly the same size as the other arms and openings, so as to be interchangeable; and so that by turning the shields 5^a a quarter-turn in one direction or the other about their pivotal pins, the openings may be uncovered to expose the glass, or covered to present the appearance of an unbroken 40 surface with the face plate 1, the color of such shields being the same as the face plate 1.

Suitable stops are provided in any desired manner to limit the movement of the shields 45 in either direction.

Fig. 1 of the drawings depicts the letters "U. S." as being displayed, and while the limitations of the drafting art prevent the proper representation of solid colors, it will 50 be evident that if the face plate and shields are properly painted in a deep and solid color throughout, an unbroken surface will appear to be had a very short distance from the eye.

55 The number of sets of openings in a sign of a given length is of course sufficient to enable any word or words to be outlined thereon, such length depending on the service to which the sign is to be put.

60 The face plate 1 is mounted in a suitable inclosed casing 8, containing any desired number of sources of artificial illumination, such as electric lamps 9.

These lights of course serve to illuminate 65 the exposed openings at night, thus outlin-

ing the legend or sign displayed, while the nature of the glass behind the openings permits the sign to be readily seen and read in the daytime.

The sign shown in the drawings has a 70 single face plate, but it will be evident that an opposite one may be also provided, should the sign be intended to be seen from two directions, as in those projecting across the sidewalk from above stores, etc. 75

From the foregoing description it will be readily seen that I have produced such a device as substantially fulfills the object of the invention as set forth herein.

While this specification sets forth in detail the present and preferred construction of the device still in practice such deviations from such detail may be resorted to as do not form a departure from the spirit of the invention, as defined by the appended 85 claims.

Having thus described my invention what I claim as new and useful and desire to secure by Letters Patent is:—

1. A radiant annunciator sign comprising 90 an opaque face plate provided with closely spaced openings throughout its area whereby any line combinations may be formed, and to allow light to penetrate therethrough, an independent revoluble shield for each opening 95 to cover the same at will, the openings and shields being so correspondingly formed and connected that the latter may be moved in the plane of the plate to uncover said openings without interference with adjacent 100 openings.

2. A radiant annunciator sign comprising 105 an opaque face plate provided with closely spaced openings throughout its area whereby any line combinations may be formed, and to allow light to penetrate therethrough, such openings being substantially circular 110 in outline and having spaced webs connected with the plate and with each other, and an independent shield for each opening positioned behind the plate and shaped to correspond to the openings, and adapted to be moved to be concealed behind the opening-webs to uncover the openings.

3. A radiant annunciator sign comprising 115 an opaque face plate provided with closely spaced openings throughout its area whereby any line combinations may be formed, and to allow light to penetrate therethrough, such openings being substantially circular 120 in outline, and being partly covered with webs radiating from the center and integral with the plate, the shape of each web being similar to but slightly greater than the intermediate opening-spaces, and an independent shield for each opening to uncover the same at will, the shields being pivotally mounted to the plate at the centers of the openings and shaped to correspond to the opening-webs, whereby they may be turned 125 130

to cover the openings or to be superimposed over the webs to uncover said openings.

4. A device of the character described comprising an inclosed casing containing a source of light, an opaque face plate thereon, an opalescent pane of a color distinct from the face plate positioned closely therewith, the plate being pressed outwardly in closely spaced circular areas throughout

its extent, each such area having a plurality of openings symmetrical with each other and with the space therebetween, and shields arranged to cover said openings or to be moved to lie behind the spaces therebetween turnably mounted in the circular areas between the pane and the plate.

In testimony whereof I affix my signature.
ROWLAND N. CHUBB.
